COMBINED GOLF PUTTER HEAD AND MIRROR ADAPTER

James Karban, 2307 S. 17th Ave.,
North Riverside, Ill. 60546

Filed Aug. 16, 1972, Ser. No. 281,104

Term of patent 14 years

Int. Cl. D21—02

U.S. Cl. D34—5 GH

FIG. 1 is a perspective view of a combined golf putter head and mirror adapter showing my new design;

FIG. 2 is a perspective view of the golf putter head with the mirror omitted for convenience of illustration;

FIG. 3 is a top plan view of the inventive golf putter head;

FIG. 4 is a front elevational view of the inventive golf putter head; the back elevational view thereof being essentially identical to FIG. 4;

FIG. 5 is an end view of the inventive golf putter head; the other end view thereof being essentially identical to FIG. 5;

FIG. 6 is a bottom view of the inventive golf putter head; and,

FIG. 7 is a cross sectional view taken along lines 7—7 of FIG. 1.

I claim:

The ornamental design for a combined golf putter head and mirror adapter, as shown and described.
